KNITTING APPARATUS

John C. Buckreus, Hobart, Ind., assignor to Bear Brand Hosiery Co., Kankakee, Ill., a corporation of Illinois

Application October 13, 1953, Serial No. 385,847

5 Claims. (Cl. 66—147)

This invention relates to improvements in knitting machines and its purpose is to provide novel apparatus and a novel method whereby tubular fabric may be knitted in great lengths without interruption of the knitting operation and while maintaining a substantially uniform tension in the fabric.

It is the intention that the long tube of knitted fabric produced by this invention be set by the usual steam treatment and then unraveled, thereby producing a crimped or crinkled yarn which may be wound on a cone during the unraveling operation and then used in the subsequent plain knitting of stockings such as ladies' sheer nylon stockings. The stockings produced with the use of this crinkled yarn are more attractive and uniform in appearance than those produced by the use of plain uncrinkled yarn. One such method of producing stockings from crinkled yarn is disclosed in United States Letters Patent No. 2,601,451 granted June 24, 1952, on an application of Frank R. Page.

In the production of hosiery with the use of crinkled yarn produced by that method, it is important that the crinkles in the yarn be substantially uniform in size and of different size than any of the stitches formed in the knitting of the hosiery, in order that the effect of the crinkles will be retained in the finished hosiery, and this requires the knitting of the initial tubular fabric under substantially uniform tension. Also, it is desirable that the crinkled yarn wound on the cone be of great length so that a full cone of yarn may be wound, and one or more stockings knitted, without the appearance of any knots in the yarn or the stockings.

It is, therefore, the primary object of the present invention to provide apparatus for knitting a long tube of fabric without substantial variation in the tension of the fabric. A further object is to provide a novel method of knitting a tubular fabric according to which the tube of fabric is revolved with the knitting cylinder so that there is no twisting or pulling on the long tube during the knitting thereof, other than that due to its own weight. Another object of the invention is to provide knitting apparatus for knitting a long tube of fabric and comprising a rotating cylinder in which the tube is suspended as it is formed and which carries a basket in which the progressively formed tube is collected. Still another object is to provide apparatus for knitting a long tube of fabric and, as it descends by gravity from the knitting position, collecting it in a cone-shaped basket which revolves with the knitting cylinder and automatically spreads and distributes the accumulating folds of the knitted tube so that the upper portion of the tube is suspended by gravity under uniform tension. Other objects relate to various features of construction and arrangement which will appear more fully hereinafter.

The nature of the invention will be understood from the following specification taken with the accompanying drawings in which one embodiment is illustrated. In the drawings,

Figure 1 shows a side elevation of the lower portion of

a knitting machine equipped with the features of the present invention, parts of the construction being removed and other parts being shown in vertical section;

Fig. 2 shows a side elevation of the apparatus illustrated in Fig. 1;

Fig. 3 shows a sectional view taken on the line 3—3 of Fig. 1;

Fig. 4 shows a transverse vertical section through the lower part of the basket embodied in the construction illustrated in Figs. 1 and 2, showing the means for supporting the basket for rotation;

Fig. 5 shows an enlarged vertical section through the knitting cylinder and associated parts of the machine illustrated in Figs. 1 and 2; and

Fig. 6 shows a partial top plan view of the construction illustrated in Fig. 5.

The invention is illustrated in the accompanying drawings as being embodied in a circular knitting machine of the Scott & Williams type, various embodiments of

20 which are shown, for example, in United States Letters Patent Nos. 1,152,850 dated September 7, 1915; 1,189,220 dated June 27, 1916; 1,238,052 dated August 21, 1917; 1,569,632, dated January 12, 1926; and 1,634,682 dated July 5, 1927.

25 As shown in the drawings, the knitting apparatus comprises a frame 10 having a tubular column 11 extending upwardly therefrom and entering the guide flange 12 which extends downwardly from the bed plate 13. The needle cylinder 15, having slots 15a for receiving the needles, extends upwardly from the bed plate 13 and is adapted to be adjusted vertically through pins 16 upon vertical adjustment of the column 11 by a mechanism which is not illustrated. A web holder bed 17 extends around the upper end of the cylinder 15 and carries the usual web holder 18 mounted around the upper end of the bearing 20 which is secured to the needle cylinder 15 by screws 21. All of these parts are found in the usual circular knitting machine of this type together with other operating parts which are not illustrated inasmuch as they do not bear directly upon the improvement of the present invention.

30 The present invention involves the provision of a metal cylinder 22 located within the knitting cylinder 15 and extending downwardly into the upper end of the column 11. This cylinder has an outwardly flared flange 22a at its upper end which bears upon the heads of the screws 21 and this frictional contact causes the cylinder 22 to rotate with the knitting cylinder 15. At its lower end, the cylinder 22 enters a coupling ring 23 which is clamped in position on the end of the cylinder by means of a clamping screw 24. A second cylinder 25 has a drive fit on the outer surface of the coupling ring 23 and extends downwardly therefrom within the column 11 and through the frame member 10 with its lower extremity attached to the hub 26 of a cage 27 adapted to contain a basket 28 in the form of a truncated cone which is open at its upper end and which is adapted to receive the knitted fabric tube 30 produced by the knitting mechanism and discharged downwardly through the cylinders 22 and 25. For the purpose of inspecting the knitted tube 30 as it moves downwardly, the upper end of the cylinder 25 is provided with an aperture 25a which is adapted to register at intervals during the rotation of the cylinder with an aperture 11a formed in the side of the column 11.

35 The cage comprises three arms 31 which are secured to the hub 26 and which extend radially outward therefrom as shown at 31a and thence downwardly and outwardly as shown at 31b. The lower ends of these arms 31 are secured to the upturned flanges 32a of bars 32 which extend radially outward from the axis of the lower part of the basket construction. The members 32 have a central aperture engaged by a trunnion 33 extending

upwardly from a thrust bearing unit 34 mounted in a plate 35 secured to the floor 36. The bottom of the basket has a hump 28d so that it rests on the cage without engaging the trunnion. At one side of the cage the flange 32a of the bar 32 extends upwardly to retain the basket 28 in position within the cage where it is adapted to rest upon the transverse members 32. The arms 31 are located 90° apart with two of them opposite each other, leaving one side of the cage open so that the basket 28 may be inserted over the upstanding flange 32a and then dropped into position on the members 32 where it will be rotated by frictional contact with the cage as the cage revolves with the cylinders 22 and 25.

The cage 28 is formed of sheet metal and is in the form of a vessel having a bottom wall 28a, an annular wall 28b in the form of a truncated cone, and a rib 28c around the top edge of the annular wall which bounds the opening through which the tubular fabric enters the basket and through which it is withdrawn.

As the knitting operation proceeds, the tube 30 of knitted fabric descends by gravity through the aligning cylinders 22 and 25 and rotates with these cylinders and the knitting cylinder 15. As it enters the basket 28, the action of centrifugal force cooperates with the force of gravity to throw the tube outwardly toward the outer annular wall of the basket so that it assumes the form of a plurality of superimposed coils or folds which allow a great length of the knitted tube to accumulate in the basket without interfering with the continuous descent of the knitted tube through the cylinders 22 and 25. Thus, the weight of the knitted tube 30 acts to maintain a substantially uniform tension on the fabric which is being knitted by the knitting apparatus at the head of the knitting cylinder so that the stitches formed in the tube 30 are substantially uniform in size. By suitably adjusting the knitting apparatus during the knitting of the tube 30, the stitches may be so regulated in size that they will differ from any of the stitches which are present in the hosiery knitted from the yarn which is produced by unraveling the tube 30 after this tube has been set by the action of heat, thus causing the crinkles of the yarn to produce the desired attractive appearance throughout the stocking, including those portions which have relatively wide or open stitches at the top and those parts which have relatively tight stitches at the ankle.

Although one form of the invention has been shown and described by way of illustration, it will be under-

stood that it may be constructed in various other embodiments coming within the scope of the appended claims.

I claim:

- 5 1. The combination in knitting apparatus, of means for knitting a fabric tube, a rotary cylinder through which said tube passes by gravity as it is formed, a cage carried by the lower end of said cylinder, and a basket removably mounted in said cage for receiving said tube.
- 10 2. The combination in knitting apparatus, of means for knitting a fabric tube, a rotary cylinder through which said tube passes by gravity as it is formed, a cage carried by the lower end of said cylinder, a bearing mounted beneath said cage to support it for rotation, and a basket removably mounted in said cage for receiving said tube.
- 15 3. The combination in knitting apparatus, of means for knitting a fabric tube, a rotary cylinder through which said tube passes by gravity as it is formed, a cage carried by the lower end of said cylinder, and a basket removably mounted in said cage for receiving said tube, said basket being in the form of an upright truncated cone.
- 20 4. The combination in a knitting machine having a rotary knitting cylinder and associated apparatus for knitting a fabric tube, of a second cylinder mounted within said knitting cylinder and rotatable therewith for receiving said tube as it is knitted, a cage carried by said second cylinder and rotatable therewith, and a tube receiving basket removably mounted in said cage and having an outwardly and downwardly flared annular wall.
- 25 5. The combination in a knitting machine, of a rotary knitting cylinder, a bearing ring mounted on the upper end of said cylinder, means associated with said cylinder and said bearing ring for knitting a fabric tube, a second cylinder through which said tube descends by gravity as it is formed, said second cylinder having its upper portion located within said first named cylinder and being provided at its upper end with an annular flange carried by said bearing ring, and a removable basket carried by said second cylinder for receiving said tube.
